(57) **CLAIM**

The ornamental design for a drawer safe, as shown and described.

DESCRIPTION

FIG. 1 is a front, top perspective view of a drawer safe, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged portion view labeled "9" in FIG. 1;

FIG. 10 is another perspective view of the drawer safe, shown in a used position; and,

FIG. 11 is another perspective view of the drawer safe, shown in a used position.

The dash-dot-dash broken lines in FIGS. 1 and 9 are for the purpose of illustrating the boundary lines of FIG. 9 in FIGS. 1 and 9. The evenly spaced broken lines are shown for the purpose of illustrating both parts of the drawer safe as well as environmental subject matter. None of the broken lines form part of the claimed design.
